UNITED STATES PATENT OFFICE

JOHN W. WARD AND BERRY A. WARD, OF MILLERSBURG, MISSOURI

GARAGE DOOR OPENING AND CLOSING DEVICE

Application filed December 10, 1929. Serial No. 412,969.

Our invention relates to improvements in "garage door opening and closing devices" wherein the weight of the car or other vehicle is utilized to open the door as the car approaches the door from without or from within.

It is well known that numerous complicated mechanisms have been devised and it is therefore an object of the present invention 10 to provide a practicable yet extremely simple device of this character by means of which the operation of opening the door, gate or the like, may be easily accomplished and the door will automatically close when the mechanism is released.

The invention will first be hereinafter more particularly described with reference to the accompanying drawings which form a part of this application and later described 20 in the annexed specification.

In said drawings:

Fig. 1 is a perspective illustrating one application of the invention;

Fig. 2, a fragmentary detail;

Fig. 3, a section on the line 3—3 of 25 Fig. 1;

Fig. 4, a longitudinal vertical section; and

Fig. 5, a similar view showing the door open due to the depression of its associated 30 platform.

In the drawings a garage or other building 10 is shown provided with right and left double doors 11 and 12. The garage is supported on a concrete base or other formation 13 which usually extends a substantial distance in front to form a drive way.

In carrying out the present invention a platform 14 is mounted in a position to be engaged by a vehicle about to enter or emerge 40 from a garage and the platform is supported in a receiving recess or well 15 in the concrete foundation 13. The platform 14 comprises a pair of longitudinally disposed spaced I-beams 16 upon which is mounted a suitable 45 flooring of lumber or other desired material. The ends of the I-beams 16 project into the concrete foundation or beneath an overhanging ledge 17 to prevent the platform from tipping up at its ends. The platform is supported by means of a central bar or cross

member 18, in a manner to be hereinafter more fully set forth. This member is placed substantially midway between the ends of the platform and maintains the same substantially balanced upon this cross member 18. 55

As shown particularly in Fig. 1, the supporting member has its ends extended and such ends are loosely received in recesses in the concrete foundation 13 and extend beneath brackets 19 and 20 fixed to the concrete foun- 60 dation and having spaced opposed sides 21 through each pair of which extends a pivot 22. Upon each pivot 22 is mounted a door operating lever 23 which has its rear and shorter end adjustably connected by means 65

of a link 24 with the cross member 18 and with its forward and longer end provided with a loop or eye 25 slidably engaging a bracket 26 located in parallel relation to the edge of the door remote from the hinges upon 70 which the door is mounted. The lever 23 performs the operation of opening and closing the door, its weight on the longer end and the employment of a spring 27 serves to close the door and the swinging upward of the lever by 75

the depression of the platform causes the loop 25 on the long end of the lever to ride upwardly along the bracket 26 and swing the door to the open position. It will be understood of course that the pivot 22 for the 80 lever 23 is supported a distance from the hinged edge of the door substantially equal to the distance from the hinged edge of the door to bracket 26. Further, by observation of Fig. 2 it will be readily understood that the lever 23 is loosely mounted on the pivot 22 and therefore can swing laterally a limited 85 amount upon its support.

As stated, the links 24 attached to and sus- 90 pended from the shorter ends of the levers 23 are pivotally connected at their other ends with the bar or cross member 18, adjacent its ends. The platform 14 is substantially bal- 95 anced on this bar 18, and the weight of the long ends of levers 23 and the force of springs 27 serve to suspend the platform in its ele- vated position substantially as shown in Figs. 1, 3 and 4. The weight of the vehicle de- presses the platform 14, as shown in Fig. 5.

While the operation of a pair of doors has 100

been described, it will be understood that the device may be used with only one door and, further, the platform instead of being substantially flush with the concrete foundation, 5 might be supported slightly above or any other desired relation, and we do not limit ourselves to what is shown in the drawings and described in the specification, but only as indicated in the appended claims.

10 We claim:

1. Door opening and closing mechanism comprising a platform supporting bar, a platform carried by said bar, brackets mounted adjacent to and over the ends of said bar, 15 levers pivotally mounted on said brackets with long ends extending toward the doors and short ends overhanging the ends of the bars, links connecting the short ends of the levers with the ends of said bar whereby the 20 platform is supported, means for slidably connecting the long ends of said levers with the swinging edges of the doors, and means associated with the long ends of the levers to overcome the weight of the platform and 25 normally close the doors.
2. With a pair of swingingly mounted doors to close an opening, a recess within the floor adjacent to the door opening, a platform loosely received within the recess with its 30 ends held against swinging movement above the recess, a bar associated with the platform, said bar having extending ends, brackets mounted adjacent to and bridged over the ends of the bar, levers pivotally mounted 35 in said brackets with short ends overhanging said bar ends and long ends extending to the swinging edges of the doors, sliding connections between the long ends of the levers and said doors, links connected with the short 40 ends of said levers and the ends of the bar to support the platform from said levers when the doors are closed, and springs acting upon the long ends of said levers to normally 45 swing the levers to the door closing and platform suspending positions.

46 In testimony whereof we affix our signatures.

JOHN W. WARD.
BERRY A. WARD.
